UNITED STATES PATENT OFFICE.

JACOB FELBEL, OF NEW YORK, N. Y.

TYPE-WRITING MACHINE.

SPECIFICATION forming part of Letters Patent No. 657,927, dated September 18, 1900.

Application filed June 5, 1899. Serial No. 719,419. (No model.)

To all whom it may concern:

Be it known that I, JACOB FELBEL, a citizen of the United States, and a resident of the borough of Manhattan, in the city of New York, in the county of New York and State of New York, have invented certain new and useful Improvements in Type-Writing Machines, of which the following is a specification.

10 The present invention relates to type mechanism for type-writing machines, and more particularly to type mechanism for "visible-writing" machines, so-called.

One object of the invention is to provide a 15 construction of the type-action wherein each type-action may be made complete and assembled in the machine as a unit and may also be removed therefrom as a unit with ease and despatch in order to be repaired or to be 20 replaced by another.

Another object is to provide a type-writing machine of relatively few parts compactly arranged and the whole of a minimum size and one in which the writing is visible to the 25 operator as it progresses, not requiring that the operator shall move any part of the body or the head beyond casting the eyes in the proper direction in order to see the line of writing being done.

30 Another object is, in a machine in which the printing-point is at the front side of the platen and in which a plurality of type upon the individual type-bars are employed, to shift the type-carriers in order to bring a different 35 set or "case" of type into position for coaction with the platen upon the operation of the keys. By preference the shift of the type-carriers is in a vertical direction.

Another object is, in a "double-case" 40 machine, to provide key-operated means for the upper-case shift which will maintain the machine in the upper-case printing position only so long as the key is depressed, and also to provide mechanism which will automatically retain the type-bars in the upper-case 45 printing position until properly released, thus providing for the automatic return of the type-bars to lower-case position after the writing of a capital at the beginning of a 50 word, and also providing for the writing of upper-case letters or characters in succes-

sion and freeing both hands for use in such writing.

Another object is to provide a novel construction and arrangement of the type-action. 55

These and other objects and advantages of my improvements will hereinafter more fully appear.

To these ends the invention includes features of construction and combinations of 60 devices hereinafter described, and more particularly pointed out in the appended claims.

The preferred form of the invention is illustrated in the accompanying drawings, forming 65 part of this specification, in which—

Figure 1 is a plan view of the machine with portions of the platen and top plate broken away, also with the whole series of type-bars broken away from the type ring or segment to more clearly exhibit the latter. Fig. 2 is 70 a bottom plan view of the under side of the machine looking upward. Fig. 3 is a central longitudinal vertical sectional view looking from the right-hand side of the machine and showing one of the type-bars and its actuating mechanism in the positions thereof at the moment of the printing of a letter by a type on the bar. Fig. 4 is a vertical cross-sectional view, the plane of the section through the frame being indicated by the line X X in 75 Fig. 3 and the section through the key-levers being indicated by the line X X in Fig. 2. Fig. 5 is a detail vertical sectional view on the line Y Y of Fig. 4 and showing a ball-separator. Fig. 6 is an enlarged plan view 80 of the detached type-segment, showing the two middle and the extreme type-bars mounted thereon and the manner of connecting them with their actuating-levers to permit of a free up-and-down movement of 85 the type-ring during the shifting operation. Fig. 7 is a diagrammatic view showing the normal position of a type-bar and other parts in full lines and showing the shifted position of parts in dotted lines for upper-case work. 90 Fig. 8 is a diagrammatic view illustrating the manner of locking the type-ring in its shifted position, the forward end of the type-bar key-lever 7 being broken away or removed. Fig. 9 is a similar view illustrating the manner of 95 releasing the locking device to allow the return of the type-ring to position for printing 100

lower-case characters. Fig. 10 is a modification in arrangement of the type-action. Fig. 11 is a further modification thereof, and Fig. 12 is a modification in the form of the abutment for the bent lever.

5 The same character of reference will be used to indicate the same part in the various figures of the drawings.

Referring to Figs. 1 to 9 inclusive, 1 indicates a base-frame of suitable construction; 10 2, uprights or standards formed or cast in one with the base; 3, a top plate or table secured to the standards 2 in any suitable manner, as by screws 4; 5, rubber feet secured to the 15 base, and 6 a platen which is suitably mounted in any suitable form of carriage. (Not shown.)

7 7 indicate key-levers made of sheet metal and formed each at its rear end with an open-ended longitudinally-extending slot 8, which 20 is formed intermediate its ends with curved or arc-shaped indentations 9, thus forming a double keyhole-slot.

10 10 indicate suitable keys or finger-pieces at the forward ends of the key-levers.

25 11 is a fulcrum-rod secured in hangers 12 by set-screws 13, the hangers being formed in one with and projecting downwardly from the top plate of the base-frame 1. The rod 11 is flattened on two opposite sides, so that when 30 the flattened sides thereof are horizontal the slotted ends of the key-levers 7 may be slipped thereover until the indentations 9 are in position over and under the rod 11, whereupon by giving the rod 11 a quarter-turn (the 35 screws 13 having been loosened) the rod engages with the said indentations 9 and locks the key-levers against endwise motion but permits a rocking motion thereof about the rod. The said screws 13 are tightened to 40 hold the rod 11 in the position thereof shown in full lines in Fig. 3.

The rear parallel portions *a* of the levers 7 are placed closer together than the parallel forward or key-bearing portions *b* thereof, and 45 said parallel portions *a* *b* are connected by oblique portions *c*. The rear parallel portions *a* of the key-levers 7 are condensed or brought closer together, so as to enable the use of a series of substantially-vertical and 50 substantially-parallel bent levers, as will appear hereinafter, while the front parallel portions *b* of the key-levers are arranged farther apart to provide the requisite space for the key heads or buttons. The machine is provided with two reed bars or combs 14 and 15 for guiding the key-levers in a vertical direction. Suitable springs 16, secured at one end 55 between cross-bars 17, which also retain the lower ends of the reed 14, press upwardly 60 against the key-levers 7 at a point forward of the fulcrum-rod 11 and between the members of the reed 14.

The shifting segment shown for supporting the type-bars will be described next.

65 At a point about midway between the front and rear standards 2 and at each side of the machine is provided a vertical guide-plate 18,

which is formed in one with or is attached to the table 3, as by screws 19, which pass through lugs 20, formed integral with the plates 18, 70 and engage with threaded holes in the under side of the table 3. The inner edges of the plate 18 are provided with vertically-extending V-shaped grooves 21 for a purpose presently to appear. Between the guide-plates 18 75 is placed a type-bar segment or part ring 22, which lies in a vertical plane and is formed or provided with vertical end plates 23, having V-shaped grooves 24 adjacent to and opposing the grooves 21 in the plates 18. In 80 each of the raceways formed by the grooves 21 and 24 are placed two balls 25, which are held at fixed distances apart by a suitable separator, as a plate 26, placed between the parts 18 and 23 and provided with perforations of larger diameter than said balls and embracing the same, as illustrated in Figs. 1, 4, and 5. The described construction permits of an up-and-down motion of the type-segment with a minimum of friction at its 90 bearings, the plate 26 rising and falling with the balls. For the purpose of limiting the up-and-down motion of the ring or segment 22 each plate 18 has an arm 27 rigidly connected therewith, as by screws 28 passing 95 through perforations in the arm and engaging threaded holes in the plate. Said arms project horizontally adjacent the plates 23, as shown in Fig. 4, and each plate 23 is provided with two lugs 29 and 30, one above and the 100 other below the corresponding arm 27, and each lug is provided with a screw-threaded perforation for the reception of an adjustable screw-stop 31 32. In the normal position of the parts the adjustable stops 31 rest or abut 105 against the top sides of arms 27 and so limit the downward motion of the segment 22, while the stops 32 strike against the under sides of the arms 27 to limit the upward motion of the 110 said segment. The separators 26 are each provided with horizontally and forwardly projecting arms 26^a, between which the arms 27 pass, as indicated in Fig. 5, the arms 26^a being at a distance apart such that the separators and balls 25 may have ample motion 115 in shifting the type-bars, as hereinafter described. The arms 26^a and 27 prevent the separators and balls from being displaced or lost.

Flat type-bars 33 (which may be ribbed, however, for strength) are pivotally connected with the segment 22 in any suitable manner; but in the preferred form of the invention these type-bars are connected with the segment in the following manner: The segment is provided or formed with a series of wedge-shaped lugs 34, separated from each other by uniform intervals or spaces and having their adjacent sides parallel, said lugs being at the upper side of the segment 22 and the segment 22 being formed in the arc of a circle whose center is at the printing-point on the platen 6. The lugs 34 are slotted transversely to about half their depth for the re-

ception of a curved bar, rod, or wire 35, which is flattened at its front and rear sides, as indicated in Figs. 1, 3, and 6. Each type-bar 33 is provided with an open-ended keyhole-slot 36, having parallel sides connecting the circular part thereof with the outer edge of the type-bar, as indicated in Fig. 8. The parallel sides of the slot 36 are at a distance apart sufficient barely to permit the insertion of the type-bar 33 over the fulcrum-rod 35 when the type-bar is in the position shown in Fig. 8—that is, in its normal position in the machine—and the circular part of the slot 36 is of a size adapting it to fit closely upon the circular edges of the rod 35 and to lock the type-bar against play upon the pivot-rod 35 whenever the type-bar is given a pivotal or swinging motion. The arc-shaped wire or rod 35 is held in position by set-screws 37, engaging threaded holes in the plates 23 and bearing against the rod. Each type-bar 33 when in normal position may be separately removed from the type-ring by lifting it out of the slot formed by the lugs 34 on each side thereof, and each type-bar is of course of a thickness to fit nicely in the slot in which it is placed, but to have sufficient freedom of motion during the operation of the machine.

In one form of the invention each type-bar 33 is provided with an upwardly and forwardly extending arm or toe 38, to which one end of a link 39 is pivotally connected, as by a rivet at 40. The rear end of said link 39 is pivotally connected to the upper end of a corresponding lever 41, as by a rivet at 42, and each lever 41 is pivotally attached to a corresponding key-lever 7 in rear of the vertical plane through the pivot-rod 35 of the type-bars, as by a rivet at 43, and each lever 41 is extended downwardly and forwardly beyond its corresponding lever 7 and is provided with an open-ended substantially horizontally extending slot 44, by means of which the lever 41 engages both sides of a horizontal rod 45, which is supported or secured in frame 1 and which forms an abutment for operating the levers 41, positively in each direction, thus avoiding the use of separate returning-springs. The shaft 45 may be provided with a series of sleeves 45^a, loose thereon, one for each lever 41 and engaging the slot thereof for the purpose of reducing the friction. The slots 44 open forwardly of the machine, and the slots 8, 36, and 44, together with the rods 35 and 9, provide means whereby each individual type-bar and its link and actuating-levers may be removed from the machine and may be replaced without disturbing any other type-bar or type-action, as by turning the bar 9 to bring its flattened sides horizontal, then lifting the desired or selected type-bar 33 vertically from its normal position to disengage it from its fulcrum-rod 35, then pushing the key-lever rearwardly of the machine to disengage the lever 41 from the rod 45, and then pulling the key-lever forward again until it is disengaged from the rod 9.

The bent or bell-crank levers 41 are of varying lengths, increasing in length from the central line of the machine in each direction toward the sides in order to keep the pivotal points 42 in the same relation to the horizontal planes through the corresponding pivotal points 40, as indicated in Fig. 3; but equal depressions of the keys 10 may be secured by varying the points of attachment 43 of the levers 41 to the levers 7, thus also producing equal rearward motion of the points 42 as the associated type-bars are thrown to the printing-point, the pivots 43 being moved rearwardly proportionately as the levers 41 increase in length between the points 42 and 43. The pivots 42 are all horizontal, while the pivots 40 become more and more angular to the horizontal as their distance from the central part of the segment 22 increases, but each always remains parallel to the pivot of the corresponding type-bar, and the links 39 are given a twist, as at 39^a, in order to bring their forward ends into parallelism with the plane of the arm 38 of the type-bar. In the case illustrated in the main views the force transmitted through the link is exerted as a pull when the type is thrown to the printing-point and as a push when it is returned to normal position by the link 39; but this may be reversed by arranging the toe or crank-arm of the type-bar below the pivot and connecting the bent lever to the key-lever and abutment, as shown at Fig. 10. The link 100 and bent lever may also be connected to the type-bar and key-lever, as shown at Fig. 11, if desired—that is, with the bent lever connected to the key-lever in front of the plane of the type-bar segment.

The operation of the type action shown in the main views is as follows: Upon the depression of a key 10 and its lever 7 the corresponding lever 41 is pressed against the abutment rod or shaft 45 and begins to slide or move transversely of the same forwardly of the machine, thus causing the lever 41 to turn upon its pivot 43 and draw the upper end 42 rearwardly of the machine. The corresponding link 39 is drawn rearwardly of the machine, thus pulling upon its associated type-bar at a point above its pivot and rotating the type-bar about the fulcrum-rod 35 and bringing a type upon the bar into contact with the paper on the platen 6 at the front side thereof. Upon the release of the depressed key its spring 16 restores the key-lever to its normal position and the force of said spring, combined with the weight of the type-bar, causes the bar and lever 41 to return to normal position, the rod 45 assisting in the operation and the sleeve on the rod reducing the friction as the lever 41 moves transversely of the rod or shaft 45.

While the type-bars are shown as lying normally in horizontal positions and as swinging upwardly and rearwardly and striking the platen in substantially a horizontal plane through the axis thereof, it is to be under-

stood that in so far as "visible writing" is concerned the type may strike the platen at any point of the platen in view of the operator, and that in case the type-bars strike the platen above the horizontal plane through the axis thereof and it is desired to have the type-bars move through not more than an angle of ninety degrees, which is the angle through which the type-bars shown in the drawings move, the plane of the pivots of the type-bars may be inclined to the vertical to the proper degree and may also be moved forwardly, and that in such case the type-bars would no longer lie horizontally but would form an angle with the horizontal.

An examination of Fig. 8 will show that the tendency of the pull of the link 39 upon the arm 38 of the type-bar is to prevent disengagement of the type-bar from its fulcrum-rod 35, although in the normal position of the type-bar the open-ended slot 36 is in position for disengagement from the fulcrum-rod 35.

The particular construction of the type-bars illustrated in the drawings will next be described, with the premise that a fixed guide 46, adjacent the printing-point, is employed in the preferred form of the invention. The guide 46 is in the shape of a V-notch in a metal plate or arm 47, secured to the table 3, as by screws 48, the bottom of the V being extended with parallel sides, as illustrated in Fig. 1, to receive the flat type-bars. Each type-bar in the machine shown in the drawings is provided with two types 49 and 50, the type 49 representing the lower-case and other characters and the type 50 representing the upper-case or capital letters and other characters. Inasmuch as the type-ring 22 is liftable or shifted upwardly for upper-case work and as the guide 46 is shown as stationary, it results that different portions of each type-bar coact with the guide according as upper-case or lower-case work is being done. For the foregoing reason the type-bars 33 are most of them bent at 52 in order to bring a sufficient length of the type-carrying end into the vertical plane when each bar is at the printing-point, (see Fig. 4,) said bends 52 being at such a distance from the type-bearing end of the bars as will provide for the shifting action aforesaid without bringing the bends themselves into the guide 46. The bends on one side of the central vertical longitudinal plane through the printing-point are in one direction, as illustrated at Fig. 6, and those at the other side of said plane are in the opposite direction. If the type-guide be mounted to shift with the segment, the bent type-carrying end of the bar may be shorter than shown. As will be understood from an examination of the type-bar shown in printing position at Fig. 4, the type-bar hubs, as well as the slots in which they are placed, radiate to a point above the bend 52, (preferably the printing-point,) and the bars are bent inwardly at points 51 near the hubs,

so that when a bar is in printing position the body thereof extends in a radial direction from the bend 52 to the bend 51, and at an angle to the hub portion thereof, in order to enable a short length of the free end of the type-bar to stand vertically. It is understood, of course, that if no central guide 46 be employed the bends 51 52 may be omitted—that is, the type-bar may be straight and the type-block be set at the proper angle thereto in order to secure the correct impressions from its type.

The type-blocks 49^a may be secured to the bar in any known or suitable way. The type-bars in their normal positions rest against a padded segment 53, which is rigidly connected with the segment 22 by arms 54 and shifts therewith.

Mechanism for shifting the segments 22 and 53 and the type-bars vertically will next be described. A transverse shaft 55 is pivotally connected with the base-frame 1, as by adjustable pivot-screws 56, at a distance below the key-levers 7 such that it will not interfere with the operation thereof, said shaft 55 being placed forwardly of the vertical plane of the ring or segment 22. The shaft 55 is provided with rearwardly-extending arms 57, which terminate in or substantially in the vertical plane of the segment 22 and substantially underneath the lines of guidance of the type-carrying segment by the plates 18. Each arm 57 is pivotally connected with a link 58, and the upper ends of the links 58 are pivotally connected with downward extensions of the plates 23, as by pivot-screws 59. The rock-shaft 55 is also provided at near one end, as the left-hand end, with a forwardly-extending arm 60, and said arm is provided with a transverse pin 61, projecting laterally on each side thereof. An upper-case shift lever 62 is connected with the shaft 11 in the same manner as are the key-levers 7 and is held up by a spring 63, connected with the cross-bar 17 of the base-frame. The lever 62 extends over the pin 61 at one side of the lever 60 and is provided with a finger-piece 64 in the keyboard of the machine. The depression of the key-lever 62 depresses the free end of the lever 60 through the medium of the pin 61 and so rocks the shaft 55 and causes the arms 57 to raise the links 58, and the links push up the segment 22 until the stops 32 strike against the under side of the arms 27 and arrest the upward motion of the segment and the downward motion of key 62. The arms 57 are of equal lengths, thus moving the ends of the segment 22 equally, and the stops 31 and 32 are so adjusted relatively to the arms 27 as that the vertical motion of the type-segment is exactly equal to the distance between the bottom lines of the faces of the type 49 and 50, thus securing the printing of upper and lower case letters in exact alignment with each other. Upon the release of the key-lever 62 the parts are returned to

normal position through the action of gravity, the friction being reduced by the ball-bearings above described.

The weight of the type-segment and of the parts carried thereby may be counterbalanced nearly, as by the force of springs 65, loosely coiled about the ends of the shaft 55 and each having one end hooking under the levers 57, as indicated in Fig. 2, and the other end engaging under a pin 66, projecting inwardly from the base-plate 1.

In order to start the segment 22 downwardly quickly upon the release of the shift-key, the following devices are provided: Each plate 18 is provided with a screw-stud 67 on the forward side thereof, and about each stud is loosely coiled a spring 68, whose free ends bear one against the under side of the adjacent arm 27 and the other against a stop 69 on the adjacent plate 18 and extends partly across the adjacent plate 23, as indicated in Fig. 4. Each plate 23 is provided with a pin 70, projecting forwardly therefrom and at a distance below the free end of the adjacent spring 68. Upon the depression of a shift-key the segment 22 is carried upward until arrested by the stops 32 and the arms 27, as aforesaid; but before the stops 32 strike the arms the pins 70 strike the springs 68 and carry them on or upward until the segment is arrested, as aforesaid, thus carrying the springs away from their stop-pins 69 and putting them under greater tension. Upon the release of the depressed shift-key the springs 68 simultaneously act to start the segment 22 downwardly and continue to act until they are arrested by their pins 69. Thus it will be seen that by the use of the counterbalancing-spring 65 the weight to be lifted upon the depression of a shift-key is reduced to a minimum, and that by the use of the springs 68, arranged as described, the segment is instantly started downward upon the release of the depressed shift-key, and that the resistance of the springs 68 to the upward movement of the segment does not begin until after the segment is well started upward by the force exerted in depressing the shift-key lever. The springs 68 may, however, be used without the counterbalancing-springs.

In order to lock the type-segment in its shifted or upper-case position, a second shift-key lever 71 is fulcrumed on the rod 11 and extends forwardly of the machine at the side of the lever 60 opposite that on which the lever 62 passes and overlies the other end of the pin 61 and is provided with a finger-piece 72. A spring 73, connected with the bar 17 aforesaid, normally holds the lever 71 in its elevated position. The shaft 55 is provided with a vertical arm 74, which is rabbeted or notched at its upper rear corner 75. A latch 76 is pivotally connected to the base-frame 1, as by screw 77, and is provided with a laterally-extending pin 78, which overlies the lever 71, and the parts are so arranged that the free end of the latch 76 is held above and

clear of the arm 74 by the key-lever 71, as illustrated in Fig. 9, and as long as the key-lever 71 is in its normal or elevated position; but a downward movement of the lever releases the latch, so that it may engage the arm 74. Upon the depression of the key-lever 71 the arm 60, shaft 55, arms 57, links 58, and segment 22 are operated to move the segment upwardly until the stops 32 come in contact with the arms 27, and simultaneously the latch 76 drops down into the position illustrated in Fig. 8, in which the end of the latch 76 abuts against one side of the rabbet 75 and prevents the springs 65 and 68 (or the weight of the parts in case the springs be not used) from returning the segment 22 to a normal or lower-case position, the tension of the spring 73, acting through the lever 71 and pin 78, not being sufficient to overcome the friction or pressure between the end of the latch 76 and the notched end of the arm 74. Upon depressing the shift-key 62 sufficiently, however, the arm 60 and shaft 55 and arm 74 are rocked forwardly slightly, relieving the pressure between arm 74 and latch 76, whereupon the spring 73 restores the lever 71 and latch 76 to their normal positions, since the slight forward motion of the arm 74 releases the latch 76, and on releasing key-lever 62 the parts are returned to normal positions by springs 65 and 68. In this way by depressing the key-lever 71 the shifting mechanism may be locked in its upper-case position and the type mechanism be manipulated to print upper-case letters and other characters continuously by the use of both hands and the type mechanism be released and be returned to its normal position by a stroke upon the key-lever 62.

79 indicates a spacing key or bar lying in front of the key-levers 7, the spacing-bar 79 being carried by levers 80, one at each side of the key-levers 7, and fulcrumed upon the same rod 11 and upheld by springs 16.

81 indicates a vertical projecting plate just forward of the type-blocks upon the levers 33, said plate being attached to the front standards 2, as by screws 82.

As illustrated in Fig. 7, the pivot 40, between the link 39 and the arm 38 of the type-bar 33, is in the normal position of the parts below the horizontal line or plane through the pivot 42 of pivotal connection between the link 39 and the lever 41. The dotted positions of the parts in said figure indicate the upper-case position thereof, and it will be observed that the new position of the pivot 40 is substantially as much above the horizontal plane through the pivot 42 as the normal position of the pivot 40 is below such plane. Since the pivot 40 must move substantially in a right line with the segment 22 and since the link 39 must pivot or swing about the point 42, it results that in shifting the type mechanism up and down the levers 41 may have a slight rearward motion; but owing to the necessary looseness of the pivots 42 43

and the looseness at the rod 45 this very slight motion will not offer material resistance to the up-and-down motion of the type-segment, and the finger-pieces of the key-levers 7 will 5 not be moved from normal position while the type-segment is in its upper-case position. Thus owing to the link and bent-lever connections between the type-bars and the key-levers the vertical shifting of the type-bar 10 carrier and type-bars is permitted without disturbance of the positions of the key-levers, which is a great desideratum. In other words, the key-levers remain in the same positions whether the type-bars be in their 15 shifted positions or in their normal or lower-case positions. Hence the stroke of a key or depth of depression is uniform in both cases, something not easily obtainable in this type of machine and which is secured in consequence 20 of the link-and-lever connections and their peculiar arrangement. When the type-bar is in its normal or lower-case position, the links incline slightly upwardly toward the rear of the machine, and when the type-bars are in their abnormal or upper-case position the links incline slightly upwardly toward 25 the front of the machine.

While in the preferred form of the invention the levers 41 are straight and occupy a 30 width of the machine at their points of attachment to the key-levers equal or substantially equal to the chord of the arc in which the type-bars are pivoted, it is understood, of course, that the invention is not wholly limited to such arrangement and to such straight bent levers 41, and consequently is not wholly limited to key-levers 7, bent as described or even having any lateral bends at all.

In the preferred form of the invention, or 40 that illustrated in the drawings, the key-levers 7 at the general location where the levers 41 are fulcrumed thereon have a collective width transversely of the machine slightly less than the chord of the arc in which the type-bars 45 are pivoted, and the chord of the arc in which the upper ends of the levers 41 are arranged is substantially the same as the said collective width. This slight inequality between the collective width of the key-levers and the 50 chord of the type-bar-pivot arc or curve is due to the fact that the levers 41 are connected with the type-bars at points above the pivots of the latter, and it is obvious that in case the said connection between the levers 41 and the type-bars were below the pivots of the latter and it were still desired to have the levers 41 straight and also to have them act 55 in parallel planes upon the type-bars the chord of the arc of the upper ends of the levers 41 and also the collective width of the key-levers 7 would be slightly greater than the chord of the arc of the type-bar pivots.

It will be observed that while the pivots 42 are all horizontal the pivots 40 are each parallel to the pivot of its associated type-bar, the links 39 thus being connected with the levers 41 by horizontal pivots and with the

type-bars by pivots which are parallel to the pivot of the type-bar in each individual case.

In the modification shown in Fig. 11 the 70 form of the bent lever is different from that in the preceding views, and it is pivotally attached to the key-lever at a lower point, the key-lever being provided with a downwardly-extending ear for this purpose.

In the modification shown in Fig. 12 the 75 lower end of the bent lever is not provided with a slot, as in the previous views, but is pivotally connected to an abutment in the form of a link 45^b, that is pivotally supported 80 at its lower end at 45^c. This link will effect a vibration of the bent lever upon a depression of the key-lever in substantially the same manner as the pin-and-slot connections in the other views.

While I prefer to make the type-action or type-movement complete as a whole before assemblage in the machine, this feature of course is not essential to the proper operation of the mechanism, and if the same be 90 not desired the joints may be detachable instead of riveted, as shown.

It will be observed that the bell-levers 41, each of which extends to a point above the pivot of its type-bar, are pivoted at their 95 lower rear portions upon a series of converging key-levers which extend rearwardly beneath the type-bar system and that a fulcrum is provided for the lower front portions 100 of said bell-levers, each of the latter being pivoted at a point between its ends to the key-lever, and one end of the bell-lever extending downwardly and the other upwardly from said pivot, and the key-lever being disposed or lying between the abutment 45 and the link 39. At the shifting operation all of the links 39 vibrate simultaneously in substantially-vertical planes about the pivots 42, the movements of the forward ends of the links and of the sliding type-bar 105 segment being first away from and then toward the key-levers. The pivots 42 are arranged substantially at right angles to the direction of the shifting movement of the type-bars, each of said pivots being arranged 110 transversely of the machine and the shifting movement being in an up-and-down direction. Each lever 41 moves in a direction at 115 an angle to the direction of movement of its key-lever, the movement of said lever 41 being fore and aft and that of the key-lever being up and down. The link 39 extends substantially in the direction of movement 120 of the bell-lever 41. Preferably the type-bars, the links 39, and the levers 41 are of 125 thin construction to economize room and reduce inertia.

The type-action may be used in a machine wherein the chord of the type-bar segment or support is equal or substantially equal to 130 the width of the key-board, and the type action may also be used in a machine wherein the platen is shifted instead of the segment and type-bars. Moreover, the type-action

may be used in a machine in which neither the platen nor the segment shifts and in which each type-bar is provided with only one type. Again, the type-bar proper may be of different form or construction—that is, it may be a jointed or compound type-bar adapted to an inking-pad. The type-bars herein shown are adapted for use in connection with inking-ribbons in the usual way.

10 Various other changes in detail construction and arrangement may be made without departing from the gist of my several improvements as set forth in the following claims.

15 What I claim as new, and desire to secure by Letters Patent, is—

1. The combination of a platen, a type-bar, a key-lever, a lever pivoted directly on the key-lever and connected to the type-bar, and 20 an abutment to which the second-named lever is loosely connected, whereby the latter has a compound movement resulting from the downward movement of its pivot on the key-lever and its loose connection to said abutment.

2. In a type-writing machine, the combination of a platen, a type-bar pivoted to strike upwardly and rearwardly, an abutment, a key-lever, a lever pivoted directly on the key-lever 30 and provided with a slot engaging said abutment so as to enable a turning and sliding movement of the lever thereon, and a connection between the second-named lever and the type-bar.

3. In a type-writing machine, the combination of a platen, a type-bar pivoted to strike upwardly and rearwardly, a key-lever, a lever pivoted directly on the key-lever, an abutment loosely connected to the second-named 40 lever and on which the second-named lever turns and slides, and a link connecting the second-named lever with the type-bar.

4. In a type-writing machine, the combination of a platen, a type-bar pivoted to strike upwardly and rearwardly of the machine, a pivoted key-lever provided with a finger-piece, a lever pivoted directly on the key-lever intermediate the fulcrum and the finger-piece thereof, and an abutment with which the second lever is loosely connected so as to turn and slide thereon during motion of the type to the printing-point.

5. In a type-writing machine, the combination of a platen, a type-bar striking upwardly and rearwardly, a key-lever fulcrumed at one end and provided with a finger-piece at the other end thereof, an abutment, a lever pivoted directly on said key-lever and provided with a loose bearing for said abutment, to enable said second lever both to turn and slide and a pivoted link connecting said second lever with the type-bar.

6. In a type-writing machine, the combination of a platen, a type-bar striking upwardly and rearwardly, a key-lever fulcrumed at one end and provided with a finger-piece at the other end thereof, a lever pivoted directly on

the key-lever intermediate the fulcrum and the finger-piece thereof, an abutment with which the second lever is loosely connected 70 so as to turn and slide thereon during the depression of the key-lever, and a pivoted link connecting the second lever and the type-bar.

7. In a type-writing machine, the combination of a platen, a type-bar pivoted to strike 75 upwardly and rearwardly, a key-lever fulcrumed at one end and provided with a finger-piece at the other end thereof, a lever pivoted on the key-lever intermediate the fulcrum and the finger-piece thereof, an abutment intermediate the pivot of the second-named lever and the finger-piece of the key-lever and with which the second lever is slidably connected during the depression of the key-lever, and a connection between the second-named lever and the type-bar.

8. In a type-writing machine, the combination of a platen, a type-bar pivoted to strike upwardly and rearwardly, a lever fulcrumed at one end and provided with a finger-piece 90 at the other end thereof, a lever pivoted on the key-lever intermediate the ends thereof, an abutment with which the second-named lever is slidably connected during the depression of the key-lever, and a link pivotally 95 connected with the type-bar above the pivot thereof and pivotally connected with the second-named lever.

9. In a type-writing machine, the combination of a platen, a series of type-bars pivoted 100 in a curved line to strike upwardly and rearwardly, a series of key-levers below the type-bars, a series of levers pivoted on the key-levers and connected each with a type-bar, and an abutment-rod below the key-levers with 105 which each of the second series of levers has a sliding action.

10. In a type-writing machine, the combination of a platen, a series of type-bars pivoted in a curved line to strike upwardly and rearwardly, a series of converging key-levers 110 below the type-bars and arranged at their rear portions to have a collective transverse width substantially equal to the chord of the arc in which the type-bars are pivoted, a second series of levers connected to the type-bars and pivotally connected with the key-levers at their rear portions, and abutments for said second series of levers.

11. In a type-writing machine, the combination of a platen, a series of type-bars pivoted in a curved line to strike upwardly and rearwardly, a series of key-levers, an abutment, a series of substantially-parallel upright levers connected with said type-bars and 125 said abutment and said series of key-levers, and having their upper ends terminating in a curve having substantially the same chord as the curve upon which the type-bars are pivoted.

12. In a type-writing machine, the combination of a platen, a series of type-bars pivoted in a curved line to strike upwardly and rearwardly, a series of key-levers, an abut-

ment, a series of levers connected with said type-bars and said abutment and said series of key-levers, and having their upper ends terminating in a curve having substantially 5 the same chord as the curve upon which the type-bars are pivoted, and links pivotally connected with the levers of the second series by horizontal pivots and with the type-bars by pivots which are parallel to the pivot of 10 the type-bar in each individual case.

13. In a type-writing machine, the combination of a platen, a series of type-bars, pivoted in a curved line to strike upwardly and rearwardly, a series of key-levers arranged 15 at one place collectively to have a transverse width substantially equal to the chord of the arc in which the type-bars are pivoted, an abutment-rod, a second series of levers slidably connected with said abutment and pivoted on said key-levers and arranged with their upper ends terminating in a curve having a chord substantially equal to the chord of the type-bar-pivot curve, and a series of 20 links connected with the second series of levers by horizontal pivots and with the type-bars by pivots parallel to the pivot of the type-bar in each individual case.

14. In a type-writing machine, the combination of a platen, a series of type-bars pivoted 25 in a curved line to strike upwardly and rearwardly, a series of key-levers below the type-bars and arranged at one place to have a collective width substantially equal to the chord of the arc in which the type-bars are pivoted, a series of levers by horizontal pivots and with the type-bars by pivots parallel to the pivot of the type-bar in each individual case.

15. In a type-writing machine, the combination of a platen, a series of type-bars pivoted 30 in a curved line to strike upwardly and rearwardly, a series of key-levers below the type-bars and arranged at one place to have a collective width substantially equal to the chord of the arc in which the type-bars are pivoted, a series of levers pivotally connected with the key-levers to vibrate in vertical planes, an abutment-rod to which the levers of the second series are connected and the upper ends of the second series of levers terminating in 35 a curve having a chord substantially equal to the chord of the type-bar-pivot arc, and a series of links connected with the upper ends of the second series of levers by horizontal pivots and with the type-bars by pivots parallel to the axis of the type-bars in each individual case.

16. In a type-writing machine, the combination of a platen, a series of type-bars pivoted in a curved line to strike upwardly and rearwardly, a series of key-levers arranged at one place to have a collective transverse width substantially equal to the chord of the arc in which the type-bars are pivoted, an abutment-rod, a second series of levers slidably connected with one of said abutment and series of key-lever elements and pivotally connected with the other of said elements and arranged with their upper ends terminating in a curve having a chord substantially equal 50 to the chord of the type-bar-pivot curve, and a series of links connected with the second series of levers by horizontal pivots and also pivotally connected with the type-bars.

17. In a type-writing machine, the combination of a platen, a series of type-bars pivoted in a curved line to strike upwardly and rearwardly, a series of converging key-levers of the second order having parallel rear portions of a collective width substantially equal to the chord of the type-bar-pivot curve, a series of

bars and arranged at one place to have a collective width substantially equal to the chord of the arc in which the type-bars are pivoted, 70 a series of levers pivotally connected with the key-levers to vibrate in vertical planes, an abutment-rod to which the levers of the second series are slidably connected, and the upper ends of the second series of levers terminating in a curve having a chord substantially equal to the chord of the type-bar-pivot arc, and a series of links connected with the upper ends of the second series of levers by horizontal pivots and also pivotally connected 75 with the type-bars.

18. In a type-writing machine, the combination of a platen, a series of thin type-bars, a slotted segment in which the type-bars are pivoted to strike upwardly and rearwardly, 80 a series of key-levers below the type-bars and arranged at one place to have a collective width substantially equal to the chord of the arc in which the type-bars are pivoted, a series of levers vibrating only in vertical planes 85 and operatively connected with the key-levers and having their upper ends terminating in an arc substantially concentric with the arc in which the type-bars are pivoted, and a series of flat links connected with the vertical levers by horizontal pivots and with the type-bars by pivots parallel with the pivot of the type-bar in each individual case, and said links being twisted where necessary to secure such parallelism. 100

19. In a type-writing machine, the combination of a platen, a type-bar pivoted to strike upwardly and rearwardly, a key-lever, an abutment below the same, a lever fulcrumed upon the key-lever and slotted to embrace the 105 abutment, and a connection between the upper end of the second-named lever and the type-bar.

20. In a type-writing machine, the combination of a platen, a type-bar pivoted to strike upwardly and rearwardly, a key-lever fulcrumed at its rear end in rear of the pivot of the type-bar, a lever pivoted to the key-lever in rear of the pivot of the type-bar, an abutment below the key-lever and forward of the 110 pivot of the second-named lever and connected with the second-named lever, and a connection between said second-named lever and the type-bar at a point above the pivot of the latter. 120

21. In a type-writing machine, the combination of a platen, a pivoted type-bar, a key-lever of the second order, an abutment therebelow, a lever pivoted on the key-lever and connected with the abutment by a slot, and a link 125 pivotally connected to the second-named lever and to the type-bar.

22. In a type-writing machine, the combination of a platen, a series of type-bars pivoted in a curved line to strike upwardly and rearwardly, a series of converging key-levers of the second order having parallel rear portions of a collective width substantially equal to the chord of the type-bar-pivot curve, a series of

levers pivoted each to a corresponding key-lever at said rear parallel portions, an abutment with which the second-named series of levers engages and the upper ends of said second series of levers being parallel and moving in vertical planes, and a connection between each of said upper ends and the corresponding type-bar.

22. In a type-writing machine, the combination of a platen, a series of type-bars pivoted in a curved line to strike upwardly and rearwardly, a series of key-levers of the second order having parallel front and rear portions connected by oblique portions and the rear parallel portions being of a collective width substantially equal to the chord of the arc in which the type-bars are pivoted, a series of straight parallel levers pivoted each to a corresponding key-lever at the rear parallel portions thereof, an abutment with which the second-named series of levers engages and the upper ends of said second series of levers terminating in a curve substantially concentric with the pivot-curve of the type-bars, and links connecting said upper ends and the corresponding type-bars.

23. In a type-writing machine, the combination of a platen, a series of type-bars pivoted to strike upwardly and rearwardly and provided each with a plurality of types, mechanism for shifting the type-bars to bring each type of the bars to one and the same printing-point, a series of key-levers fulcrumed in the fixed framework of the machine, and a series of levers intermediate the key-levers and the type-bars and connected with each.

24. In a type-writing machine, the combination of a platen, a series of type-bars arranged to strike upwardly and rearwardly and provided each with a plurality of types, mechanism for shifting the type-bars vertically to bring each type to one and the same printing-point, a series of key-levers fulcrumed in the fixed framework of the machine, and a series of levers intermediate the key-levers and the type-bars and connected with each.

25. In a type-writing machine, the combination of a platen, a series of type-bars pivoted to strike upwardly and rearwardly, a vertically-movable segment to which the type-bars are connected, mechanism for moving said segment upwardly, a counterbalance for said segment, and a returning-spring for the said segment normally disengaged therefrom and put under tension thereby after the segment has moved upwardly a predetermined distance from its normal position.

26. In a type-writing machine, the combination of a platen, a series of type-bars pivoted to strike upwardly and rearwardly at the front side of said platen and provided each with a plurality of types, mechanism for shifting the type-bars to bring each type of each bar to one and the same printing-point, a series of key-levers extending beneath the type-bars and fulcrumed at their rear ends in the fixed framework of the machine, a series of

levers engaging said key-levers, and horizontally-disposed links connecting said second series of levers and the type-bars.

27. In a type-writing machine, the combination of a platen, a series of type-bars arranged to strike upwardly and rearwardly at the front side of said platen and provided each with a plurality of types, mechanism for shifting the type-bars in an up-and-down direction to bring each type to one and the same printing-point, a series of key-levers fulcrumed in the fixed framework of the machine, a series of levers engaging with the key-levers, and horizontally-disposed connecting rods or links between the second-named series of key-levers and the type-bars.

28. In a type-writing machine, the combination of a platen, a series of type-bars pivoted below the platen and striking at the front side thereof and provided each with a plurality of types, mechanism for shifting the type-bars in a up-and-down direction to bring each type to one and the same printing-point, a series of key-levers fulcrumed in the fixed framework of the machine, an abutment rod or shaft, a series of levers slidably connected with one and pivotally connected with the other of said key-lever and abutment elements, and a series of links or connecting-rods intermediate the second-named series of levers and the type-bars.

29. In a type-writing machine, the combination of a platen, a series of type-bars arranged to strike at the front side of said platen and provided each with a plurality of types, mechanism for shifting the type-bars in an up-and-down direction to bring each type to one and the same printing-point, a series of key-levers fulcrumed in the fixed framework of the machine, a series of levers fulcrumed upon the key-levers, an abutment rod or shaft with which the second-named series of levers engage, and connecting-links intermediate the second-named series of levers and the type-bars.

30. In a type-writing machine, the combination of a platen, a series of type-bars arranged to strike at the front side of said platen, mechanism for shifting the type-bars in an up-and-down direction to bring each type to one and the same printing-point, a series of key-levers of the second order fulcrumed in the fixed framework of the machine, and a series of levers intermediate the key-levers and the type-bars and connected with each.

31. In a type-writing machine, the combination of a platen, a series of type-bars arranged to strike at the front side of said platen and provided each with a plurality of types, mechanism for shifting the type-bars in an up-and-down direction to bring each type to one and the same printing-point, a series of key-levers of the second order fulcrumed in the fixed framework of the machine, an abutment rod or shaft, a series of levers movably connected with one and pivotally connected with the other of said key-lever and abutment ele-

ments, and connections between the second-named series of levers and the type-bars.

32. In a type-writing machine, the combination of a platen, a series of type-bars arranged to strike at the front side of said platen and provided each with a plurality of types, mechanism for shifting the type-bars in an up-and-down direction to bring each type to one and the same printing-point, a series of key-levers of the second order, a series of levers pivotally connected to said key-levers, an abutment rod or shaft with which the second-named series of levers engage slidably, and connections between said second-named series of levers and the type-bars.

33. In a type-writing machine, the combination of a platen, a series of type-bars arranged to strike at the front side of said platen and provided each with a plurality of types, mechanism for shifting the type-bars vertically to bring each type to one and the same printing-point, a series of key-levers of the second order fulcrumed in the fixed framework of the machine, an abutment-rod, a series of levers slidably connected with one and pivotally connected with the other of said series of key-lever and abutment elements, and links connecting said second-named series of levers and the type-bars.

34. In a type-writing machine, the combination of a platen, a series of type-bars arranged to strike at the front side of said platen and provided each with a plurality of types, mechanism for shifting the type-bars in an up-and-down direction to bring each type to one and the same printing-point, a series of key-levers of the second order fulcrumed in the fixed framework, a series of levers pivotally connected to said key-levers, an abutment rod or shaft with which the second-named series of levers is connected, and links connected to said second-named series of levers and to the type-bars.

35. In a type-writing machine and in a case-shifting mechanism, the combination of a pair of fixed plates having ball-guiding grooves therein, a shifting plate having ball-guiding grooves therein opposing those in the fixed plates, balls in said grooves, ball-separating plates between the fixed and movable plates and having projections, stop-arms on the fixed plates adapted to engage with the arms on the ball-separators, and stops on the shifting plate for engaging the said arms.

36. In a type-writing machine and in a case-shifting mechanism, a rock-shaft operatively connected with the shifting element of said mechanism, an arm on said shaft, a latch normally out of contact with but adapted to engage the said arm and hold the same and the shaft in one position, a shift key-lever adapted to rock said arm and also to release said latch; the construction and arrangement being such that when the key-lever is in its normal position it holds the latch out of engagement with the arm, but when the shift-key is depressed it rocks the arm and permits the

latch to pass into engagement with the arm and lock the same and the parts shifted by the key-lever.

70

37. In a type-writing machine and in a case-shifting mechanism, a spring-pressed arm connected to the part to be shifted, a latch normally out of engagement with said arm but adapted to engage said arm and hold the shifted part in its abnormal position, and a spring-actuated key-lever for rocking said arm and moving the part to be shifted, said key-lever releasing the said latch so that upon the depression of the key-lever the latch may come into operative relation with the arm, and a second spring-actuated shifting key-lever also adapted to rock said arm and thereby release the first-named shifting-lever and its connected parts from the control of said latch.

75

38. In a type-writing machine and in a case-shifting mechanism, the combination of spring-actuated arms 60 and 74, the latter having a notch 75, a pivoted latch 76 having a pin 78, a spring-pressed shifting key-lever 71 with which the pin 78 contacts so as to keep the latch normally out of engagement with the arm 74, a projection 61 on the arm 60 adapted to be engaged by the under side of the lever 71 when depressed, and a spring-pressed shifting key-lever 62 also adapted to act on the arm 60, to relieve pressure of the arm 74 against the latch, so as to release the same and enable it and the lever 71 to return to normal position, and the shifted element to return to normal position upon release of the key-lever 62.

80

39. In a type-writing machine, the combination of a platen, a shifting type-bar segment, links connected thereto, arms 57 connected to said links, a rock-shaft 55 having a rocker-arm 60 and a rocker-arm 74, a spring for said rocker-arms, a pair of spring-pressed key-levers 62 and 71 arranged adjacent to each other and adapted each to depress the arm 60 and rock the shaft and the arms 57 and 74 and thus raise the type-bar segment, a latch adapted to engage the arm 74 but held normally out of engagement by the lever 71 when in its normal position, whereby when the lever 62 is operated to shift the type-bar segment the locking mechanism is inoperative, but when the lever 71 is depressed to rock the arm 60 and the arms 57 and 74, the latch drops down into operative engagement with the arm 74 and prevents said arm and its key-lever and connected parts from returning to normal position until the lever 62 is slightly depressed and rocks the arm 74 away from the latch and thus allows the key-lever 71 and the latch to return to normal position, whereupon the segment may return to normal position upon the release of the key-lever 62.

85

40. In a type-writing machine, the combination of a platen, a vertically-shifting type-bar segment, the type-bars, the links 39, the levers 41, the key-levers 7 to which the levers

90

95

100

105

110

115

120

125

130

41 are pivotally connected, the abutments for the levers 41, means for guiding the segment vertically up and down, the rock-shaft 55, the rocker-arms 57, the links 58, the 5 rocker-arm 60, the rocker-arm 74, the latch 76, and the shifting key-levers 62 and 71, all operating in substantially the manner described.

41. In a type-writing machine, the combination of a vertically-shifting type-bar segment provided with side guides adapted to guides on the framework, a spring 68, said spring being normally inactive but put under tension during the shifting movements of the 10 type-segment and adapted only to start the segment down quickly and allow it to complete its movement by the force of gravity upon release of the shifting mechanism.

42. In a type-writing machine, the combination of a vertically-shifting type-bar segment having side guide-plates 23, guide-plates 18 on the framework, a spring 68 secured to the frame guide-plate and having its free end extending over the guide-plate 23, a projection 70 on the guide-plate 23 arranged a suitable distance away from the free end of the spring when the segment is in its lower position but adapted to contact with said spring and flex the same at a suitable time 15 in the upward movement of the segment, so that upon the release of the shifting mechanism the said spring may operate quickly to start the segment downwardly.

43. In a front-strike type-writing machine, the combination of a platen, a segment arranged below said platen, a series of type-bars pivotally supported upon said segment and having bends 52 such that the upper portion of the type-bar stands substantially vertical when in printing position, and also having bends 51 near their hub portions, the hub portions of said type-bars radiating to a point above said bend 52, and the body portions of the type-bars when in printing position extending radially from the bends 51 to the bends 52.

44. In a type-writing machine, the combination of a platen, a series of type-bars pivoted in a vertically-disposed plane to strike 50 at the front side thereof, a series of horizontally-disposed links pivotally connected with the type-bars by pivots which are parallel with the axes of the type-bars in each individual case, a series of vertically-disposed 55 levers terminating at their upper ends in an arc substantially concentric with the arc of the type-bar pivots and with which the said links are connected by horizontal pivots, and key-levers and connections for actuating said 60 vertically-disposed levers and said type-bars.

45. In a type-writing machine, the combination of a platen, a vertically-disposed slotted curved segment lower than the same, a series of thin type-bars pivotally connected 65 with the segment to strike at the front side of said platen and having projecting radial toes or arms, a series of parallel, vertically-

disposed thin levers terminating in an arc substantially concentric with the arc of the type-bar pivots, flat links connected with said 70 levers by horizontal pivots and twisted into parallelism with said arms or toes and connected therewith by pivots at right angles to the planes of said arms, key-levers, and connections for operating said vertically-disposed levers and the type-bars. 75

46. In a type-writing machine, the combination of a series of type-bars provided each with an open-ended keyhole-slot, a slotted segment or ring, a flattened pivot-rod on said 80 segment or ring and forming the fulcrum of the type-bars, a series of key-levers having open-ended longitudinal keyhole-slots at one end thereof, a revoluble flattened fulcrum-rod forming the fulcrum of said key-levers and 85 engaging said slots, a series of levers pivoted to the key-levers and provided each with an open-ended slot, a rod engaging the slots of the second-named series of levers, and links connecting the type-bars and the second-named 90 series of levers.

47. In a type-writing machine, the combination of a framework, a flat-sided fulcrum-rod revoluble in said framework, a key-lever provided with a double keyhole-slot open at 95 one end and adapted to engage with said fulcrum-rod, a type-bar provided with an open-ended keyhole-slot, a flattened fulcrum for engaging said slot, a lever pivotally attached to the key-lever and having an open-ended 100 slot, an abutment for engaging with said lever-slot, and connections between the type-bar and the second-named lever.

48. In a type-writing machine, the combination of a platen, a series of type-bars each 105 provided with a plurality of types, a series of key-levers extending rearwardly beneath the type-bar system, connections extending upwardly from the key-levers to the type-bars, and mechanism for shifting said type-bars independently of the key-levers and toward and 110 away therefrom.

49. In a type-writing machine, the combination of a platen, a series of rearwardly-striking type-bars each provided with a plurality 115 of types, a series of converging key-levers extending rearwardly beneath the type-bar system, a series of levers connected to said key-levers and extending upwardly, links connecting said upwardly-extending levers to said type-bars, and means for shifting said type-bars in an up-and-down direction, all of said links being constructed to vibrate simultaneously at the shifting operation. 120

50. In a type-writing machine, the combination of a platen, a series of type-bars each provided with a plurality of types, a series of key-levers extending rearwardly beneath the type-bars, connecting devices arranged in rear of the type-bars and extending from the 130 type-bars to the key-levers, and mechanism for shifting said type-bars in an up-and-down direction.

51. In a type-writing machine, the combina-

- tion of a platen, a series of type-bars each provided with a plurality of types, a series of key-levers extending rearwardly beneath said type-bars, links extending rearwardly from the type-bars and connected to the key-levers, and mechanism for shifting said type-bars in an up-and-down direction, all of said links being constructed to vibrate simultaneously at the shifting operation.
52. In a type-writing machine, the combination of a platen, a series of type-bars arranged to strike rearwardly and each provided with a plurality of types, a series of upright key-operated levers arranged in rear of the type-bars, links connecting said levers to said type-bars, and means for shifting said type-bars, said links being constructed to vibrate at the shifting operation and the pivots about which they vibrate being arranged substantially at right angles to the direction of the shifting movement of the type-bars.
53. In a type-writing machine, the combination of a platen, a series of rearwardly-striking type-bars each provided with a plurality of types, mechanism for shifting said type-bars in an up-and-down direction, a series of key-levers, and connections whereby said key-levers are enabled to swing said type-bars in either shift position thereof, said connections comprising both a series of levers which move in a direction at an angle to the direction of movement of the key-levers, and also a series of links extending substantially in the direction of movement of said second series of levers and connecting the latter to the type-bars.
54. In a type-writing machine, the combination of a platen, a series of rearwardly-striking type-bars each provided with a plurality of types, mechanism for shifting said type-bars in an up-and-down direction, a series of links connected with the type-bars by pivots which are parallel with the axes of the type-bars in each individual case, a series of upwardly-extending levers with which said links are connected by horizontal pivots, whereby said links are enabled to vibrate in substantially-vertical planes at the type-bar-shifting operation, and key-levers connected to said upwardly-extending levers.
55. In a type-writing machine, the combination of a platen, a segment arranged forwardly thereof, a series of slots formed or provided in said segment, a series of thin type-bars pivotally arranged in said slots and arranged to strike at the front side of said platen and each of said type-bars being provided with a plurality of types, means for shifting said segment in an up-and-down direction, radial toes or arms provided upon said type-bars, a series of substantially-parallel upright thin levers whose upper ends terminate in an arc substantially concentric to the arc of the type-bar pivots, flat links connected with said levers by horizontal pivots and twisted into parallelism with said radial arms or toes and pivoted thereto, and a series of key-levers connected to said upwardly-extending levers.
56. In a front-strike type-writing machine, the combination of a platen, a vertically-arranged segment provided with a series of slots which radiate substantially to the printing-point, a curved fulcrum-rod arranged upon said segment, and a series of type-bars placed in said slots and engaging said rod and having bends 52, such that the upper portions of said type-bars stand in a substantially-vertical line when in printing position, and also having bends 51 near their hubs, the body portions of the type-bars extending radially between said bends 51 and 52.
57. In a front-strike type-writing machine, the combination of a series of type-bars, a series of key-levers, independent connections from the key-levers to the type-bars, an up-and-down-movable segment upon which said type-bars are pivotally supported, a rock-shaft journaled in the framework, and arms fixed upon said shaft and connected to said segment.
58. In a front-strike type-writing machine, the combination of a platen, a series of type-bars, an up-and-down-sliding segment upon which said type-bars are pivotally supported, key-operated mechanism for sliding said segment, and relatively-fixed key-levers connected to said type-bars.
59. In a front-strike type-writing machine, the combination with a platen, of a series of type-bars, a segment upon which said type-bars are pivotally supported, rock-shaft 55, arms 57, links 58, and means for operating said rock-shaft.
60. In a type-writing machine, the combination of a platen, a series of type-bars, a series of key-levers extending rearwardly below the type-bars, a series of bell-levers arranged behind the type-bars and pivoted at their lower rear portions upon the said key-levers, a fulcrum for the lower front portion of each bell-lever, and a series of links pivotally engaged at their rear ends to said bell-levers and at their forward ends to said type-bars.
61. In a type-writing machine, the combination of a platen, a series of type-bars arranged to strike rearwardly, a series of converging key-levers extending rearwardly beneath the type-bars, a series of substantially-vertical levers pivoted at their lower ends to said key-levers and having a fulcrum, and a series of links connecting said substantially-vertical levers to said type-bars.
62. In a type-writing machine, the combination of a platen, a type-bar pivoted to strike upwardly and rearwardly, a key-lever, a lever pivoted between its ends on the key-lever and provided below said pivot with a slot, an abutment arranged within said slot, and a connection between the upper end of the second-named lever and the type-bar.

63. In a type-writing machine, the combination of a platen, a type-bar pivoted to strike upwardly and rearwardly, a key-lever, a lever pivoted on the key-lever, an abutment for actuating the second-named lever on the depression of the key-lever and on which the second-named lever moves, and a link connecting the second-named lever with the type-bar, said key-lever being disposed between 5 said abutment and said link.

64. In a type-writing machine, the combination of a platen, a type-bar pivoted to strike upwardly and rearwardly of the machine, a pivoted key-lever provided with a finger-piece, an upright lever pivoted on the key-lever intermediate the fulcrum and the finger-piece thereof and extending to a point above the pivot of the type-bar, and an abutment with which the second lever is loosely 15 connected so as to turn and slide thereon dur- 20

ing motion of the type-bar to the printing-point.

65. In a type-writing machine, the combination of a platen, a type-bar striking upwardly and rearwardly, a key-lever fulcrumed at one 25 end and provided with a finger-piece at the other end thereof, an abutment, a lever pivoted on said key-lever and provided with a bearing for said abutment, and a pivoted link extending rearwardly from the type-bar 30 and connected at its rear end to said second lever.

Signed in the borough of Manhattan, in the city of New York, in the county of New York and State of New York, this 3d day of June, 35

A. D. 1899

JACOB FELBEL.
